UNITED STATES PATENT OFFICE

117,978

DESIGN FOR A COMBINED PERFUME BOTTLE AND HOLDER THEREFOR

Robert B. Karoff, New York, N. Y.

Application June 4, 1938, Serial No. 77,570

Term of patent 3½ years

To all whom it may concern:

Be it known that I, Robert B. Karoff, a citizen of the United States of America and a resident of the city, county, and State of New York, have invented a new, original, and ornamental Design for a Combined Perfume Bottle and Holder Therefor, of which the following is a specification, reference being had to the accompanying drawing, forming a part thereof.

Figure 1 is a perspective view of the combination container showing my new design the cover of the external container being removed and exposing an interior container for perfumes.

I claim:

The ornamental design for a combined perfume bottle and holder therefor, substantially as shown and described.

ROBERT B. KAROFF.
